UNITED STATES PATENT OFFICE.

JOSEPH FREDRICK WRIGHT, OF CINCINNATI, OHIO.

DESIGN FOR A HANDBAG OR SIMILAR ARTICLE.

56,261.

Specification for Design.

Patented Sept. 14, 1920.

Application filed September 18, 1919. Serial No. 324,703. Term of patent 3½ years.

To all whom it may concern:

Be it known that I, JOSEPH FREDRICK WRIGHT, a citizen of the United States, residing at Cincinnati, in the county of Hamilton and State of Ohio, have invented a new, original, and ornamental Design for a Handbag or a Similar Article, of which the following is a specification, reference being had to the accompanying drawing, forming a part thereof.

Fig. 2 is a face view of the other side thereof.

I claim:

The ornamental design for a handbag or similar article as shown.

JOSEPH FREDRICK WRIGHT.
